UNITED STATES PATENT OFFICE.

BIRGER BARK, OF CHICAGO, ILLINOIS, ASSIGNOR TO THE BRUNSWICK-BALKE-COLLENDER COMPANY, OF OHIO.

DESIGN FOR A COUNTER.

SPECIFICATION forming part of Design No. 23,510, dated July 24, 1894.

Application filed June 25, 1894. Serial No. 515,700. Term of patent 7 years.

To all whom it may concern:

Be it known that I, BIRGER BARK, a citizen of the United States, residing at Chicago, in the county of Cook and State of Illinois, have **5** invented a certain new and useful Design for Counters, of which the following is a description, reference being had to the accompanying drawing, forming part of this specification.

My newly invented design relates more particularly to counters for bar fixtures but is applicable to other counters as well.

The design is fully shown in the perspective view of a counter in the accompanying drawing.

5 The counter consists of a substantially flat top supported along its forward side upon the upper ends of a series of brackets and at its ends by the end walls of the counter, and a front side composed of said brackets and **o** sections of horizontal panel and molded work set in between them. There is one of the brackets at each end of the counter and several intermediate ones arranged at equal distances apart, said brackets serving to separate the front side of the counter into a number of similar sections or divisions. The front faces of the brackets project from the surface of the counter and have the appearance of ornamental pilasters separating its **o** several sections and supporting its top. The rear sides of the brackets, at least of the end ones, which are the ones exposed, are substantially vertical from top to bottom. The lower ends of the front sides of all the **5** brackets are vertical, and from these front vertical portions the faces of the brackets incline upwardly and outwardly to the under surface of the counter-top, terminating in horizontal turned pieces abutting against the under side of said top. The lower portion of each section of the front side of the counter consists of a plain vertical panel co-incident with the vertical lower ends of the bracket-faces. The portion of the section between **5** the upper edge of this vertical panel and the under surface of the counter-top is composed of several members, but as a whole has an outward inclination conforming to the inclined faces of the brackets. The first mem- **o** ber above the lower vertical panel is a horizontal ornamented molding having an approximately vertical face slightly separated from the vertical panel below it by a narrow

ogee molding at its lower edge. Next above this ornamented surface is a horizontal plain **55** surface of about the same width as the ornamented one and inclined outwardly from its lower to its upper edge. Above this and separated from it by a narrow molding is a second approximately vertical ornamented **60** surface similar to the lower one, while above it is a second plain outwardly inclined surface connecting it with the under surface of the counter-top. The forward faces of the brackets at the junction of their inclined and vertical portions are suitably carved or shaped to conform to the molding in line with them along the front side of the counter at the upper edges of the lower vertical panels, as shown. The outer sides of the two end **70** brackets have plain surfaces and constitute the forward portions of the end walls of the counter, the portions of said end walls in rear of the brackets inclosing plain rectangular panels. Below the latter are thin vertical **75** base-blocks surmounted by molded caps, to conform to the vertical panels along the lower portion of the front side of the counter.

The distinguishing feature of the design **8c** consists in the series of brackets whose forward faces have the lower vertical portions and the outwardly inclined portions connecting the same with the under surface of the counter-top, the latter resting at its forward side upon the upper ends of said brackets, **85** and the sections of the front side of the counter set in between said brackets in rear of their front faces so as to project the same from the surface of the counter, each of said sections consisting of a lower vertical panel **90** co-incident with the vertical lower ends of the brackets, and an outwardly inclined portion connecting said panel with the under surface of the counter-top, said inclined portion being composed of a series of alternate horizontal **95** ornamented and plain surfaces separated from each other by distinct lines or moldings.

Having thus fully described my invention, I claim—

The design for a counter herein shown and **100** described.

BIRGER BARK.
